UNITED STATES PATENT OFFICE

97,585

DESIGN FOR A METALLIC MESH FABRIC

Alfred F. Reilly, North Attleboro, Mass., assignor
to Evans Case Company, a corporation of Mas-
sachusetts

Application October 17, 1935, Serial No. 59,098

Term of patent 3½ years

To all whom it may concern:

Be it known that I, Alfred F. Reilly, a citizen of the United States, residing at North Attleboro, in the State of Massachusetts, have invented a new, original, and ornamental Design for Metallic Mesh Fabric, of which the following is a specification, reference being had to the accompanying drawing, forming a part thereof.

In the accompanying drawing Figure 1 is a plan view of a fragment of metallic mesh fabric.

Fig. 2 is a plan view on an enlarged scale of one of the principal elements of the metallic mesh fabric.

Fig. 3 is a side elevation of the element of Fig. 2.

The mesh consists of a plurality of elements A each of which bears an ornamentation substantially as indicated in Figs. 1 and 2. Each element has its exposed surface arched as illustrated at B in Fig. 3. Receding from the corner of each element A are inwardly curved arms C the adjacent arms of adjacent elements being loosely connected by rings D. It will be observed in Fig. 1 that portions of two rings D appear between each pair of adjacent elements A.

I claim:

The ornamental design for a metallic mesh fabric substantially as illustrated and described.

ALFRED F. REILLY.
